UNITED STATES PATENT OFFICE.

CHARLES W. LANPHER, OF NORWICH, NEW YORK, ASSIGNOR TO COAL DEALERS SUPPLY COMPANY, OF BINGHAMTON, NEW YORK.

BAG HOLDER OR STAND.

SPECIFICATION forming part of Letters Patent No. 765,388, dated July 19, 1904.

Application filed December 26, 1902. Serial No. 136,699. (No model.)

To all whom it may concern:

Be it known that I, CHARLES W. LANPHER, a citizen of the United States, residing at Norwich, in the county of Chenango and State of New York, have invented a new and useful Bag Holder or Stand, of which the following is a specification.

The invention relates to improvements in bag holders or stands.

10 The object of the present invention is to improve the construction of bag holders or stands for supporting a bag in an upright open position while the same is being filled and to provide an exceedingly simple and inexpensive one of great strength and durability capable of being quickly adjusted to arrange it for holding a bag in proper position.

15 A further object of the invention is to provide a bag holder or stand of this character which after it has been adjusted for holding a particular kind or size of bag may be readily clamped or locked in such adjustment.

20 With these and other objects in view the invention consists in the novel construction and arrangement of parts hereinafter fully described, illustrated in the accompanying drawings, and particularly pointed out in the claims hereto appended, it being understood that changes in the form, proportion, and minor 25 details of construction within the scope of the claims may be made without departing from the spirit or sacrificing any of the advantages of the invention.

30 In the drawings, Figure 1 is a perspective view of a bag-holder constructed in accordance with this invention, a bag being shown in dotted lines. Fig. 2 is a vertical sectional view of the stand, the upper and lower arms being arranged horizontally in full lines and the standard and the upper arms being shown at a different adjustment in dotted lines. Fig. 3 is an enlarged detail view illustrating the construction for pivotally connecting the arms with the standard.

35 40 45 Like numerals of reference designate corresponding parts in all the figures of the drawings.

1 designates a vertical standard connected at its ends with upper and lower arms 2 and

3, and preferably constructed of tubular metal; 50 but it may consist of a solid rod of metal or be constructed of any other desired material. The upper and lower arms, which are also preferably constructed of tubular metal, may be made of any other material, and they are 55 pivotally connected with the ends of the standard and are curved forward at points at opposite sides of the same to form a broad base and to provide a pair of supporting arms adapted to extend through handles of a bag, 60 as illustrated in dotted lines in Fig. 1 of the drawings. The lower arms have inner threaded ends 4, which screw into opposite arms or portions of a T-coupling 5, which also receives the lower threaded end 6 of the 65 standard, and by this construction the standard is adapted to swing backward and forward 70 to arrange it in an upright or a forwardly-inclined position, as illustrated in Fig. 2 of the drawings. By swinging the standard forward and arranging it at an inclination the upper bag-supporting arms are brought nearer the base. The threading of the parts may be relied upon to provide a pivotal connection of sufficient stiffness to retain the parts 75 in their adjusted position; but it is preferable to extend the threaded portions of the lower arms and the lower end of the standard sufficiently to receive clamping-nuts 7 and 8. The 80 clamping-nuts, which are screwed on the ends of the parts before the same are assembled, are adapted after the parts have been properly adjusted to suit a particular bag to be screwed against the coupling to clamp the parts in their adjusted positions. The curved arms 85 form an approximately semicircular base, which is open to receive the bag and permit the same to be arranged close to the standard.

The upper end 9 of the standard is threaded to engage a coupling 10 of T shape, which 90 receives the inner threaded ends 11 of the upper arms 2. The upper arms 2 and the upper end of the standard are provided with clamping-nuts 12 and 13, constructed and arranged similar to those heretofore described, and all 95 of the clamping-nuts are preferably hexagonal or octagonal; but any form of polygonal nut may be employed to adapt the locking devices

for the reception of a wrench. Suitable grips or handles may, however, be used, and any other desired means may be employed for clamping the parts in their adjusted position.

- 5 The upper bag-supporting arms are curved to form an approximately semicircular top for the bag holder or stand, and they are adapted to be readily swung upward and downward to arrange them at the desired elevation for 10 supporting a bag in an upright open position for being filled. In adjusting the bag holder or stand the operator stands upon the lower arms 3 and grips the upper arms, drawing the same forward or moving them backward to 15 swing the standard to the desired position and swinging the upper bag-supporting arms upward or downward to arrange them in proper position for receiving the handles of the bag, and the device is adapted to hold a bag in 20 proper position to be conveniently filled, and such position will be maintained until the bag has received its last shovelful of coal. After the bag holder or stand has been once adjusted to suit a particular kind of bag the bags may 25 be quickly placed on the upper supporting-arms 2, and it will obviate the necessity of employing a man for holding bags while the same are being filled.

It will be seen that the bag holder or stand, 30 which is exceedingly simple and inexpensive in construction, possesses great strength and durability and is capable of being quickly adjusted to arrange the parts in proper position for supporting a flexible bag in an open 35 upright position for filling without sliding and fastening devices to permit such a sliding movement and that after the parts have been adjusted they may be clamped in such position. Furthermore, it will be clear that the 40 upper bag-supporting handles or arms are capable of being swung upward and downward and that this effect is greatly increased by the backward and forward oscillatory movement of the standard. Also the back- 45 ward and forward movement of the standard is effected by the operator without removing his hands from the upper bag-supporting arm, and after this adjustment has been obtained the final adjustment of the bag-supporting 50 arms may be made by simply drawing upward or pushing downward on the same. The base formed by the lower arms is open to receive the bag, and the lower arms are arranged in convenient position to permit the operator 55 to stand upon them and hold the bag holder or stand while the parts are being adjusted.

The upper and lower arms, which are hinged to the standard, are independently movable or adjustable and are adapted to permit the 60 base to conform to the supporting-surface and to enable the upper arms to support a bag properly.

What I claim is—

1. A bag holder or stand comprising a stand- 65 ard, a base provided with independently-ad-

justable portions movable in a vertical direction and arranged in a horizontal position at each side of the standard, means for holding the adjustable portions at any intermediate point, and means carried by the upper portion 70 of the standard for holding a bag.

2. A bag holder or stand comprising a stand- 75 ard, a base provided with independently-adjustable portions arranged in a horizontal position at each side of the standard, and inde- 80 pendently-adjustable upper bag-supporting arms pivoted to the standard at each side there- of and arranged to swing upward and down- ward and forming handles, substantially as described.

3. A bag holder or stand comprising a stand- 85 ard, independently-adjustable lower arms movable in a vertical direction and arranged at each side of the standard and forming an open base, means for holding the lower arms 90 at any adjustment, and upper supporting-arms movably connected with the standard at each side thereof and forming handles arranged to receive a bag.

4. A bag holder or stand comprising inde- 95 pendently-adjustable lower arms forming an open approximately U-shaped base, independ- 100 ently-adjustable upper bag-supporting arms forming on approximately U-shaped top por- 105 tion, and a standard pivoted to the said arms and arranged to swing backward and forward and permitting the upper arms to swing upward and downward, substantially as de- 110 scribed.

5. A bag holder or stand comprising inde- 100 pendently-adjustable lower arms forming a base, independently-adjustable upper bag-sup- 105 porting arms, a standard, and couplings connect- 110 ing the arms with the standard and pivot- ally connecting the parts to permit the standard 115 to swing backward and forward, and the upper arms to swing upward and downward, sub- 120 stantially as described.

6. A bag holder or stand comprising a base 120 having independently-adjustable portions, an upper bag-supporting portion, an intermediate connecting portion movably connected with the base and with the upper bag-supporting portion and arranged to swing backward and forward, and permitting the upper bag-sup- 125 porting portion to swing upward and downward, and means for locking the parts in their adjusted positions, substantially as described.

7. A bag holder or stand comprising lower 130 arms having inner threaded portions, upper arms provided with threaded inner ends, a standard provided with threaded ends, cou- 135 plings pivotally connecting the arms with the standard, and clamping-nuts mounted on the said threaded portions and arranged to engage the couplings to lock the parts in their ad- 140 justment, substantially as described.

8. A bag holder or stand comprising a base, a standard rising from the base, upper inde- 145 pendently-adjustable arms, movable in a ver- 150

tical direction, and connected to and extending from each side of the standard, the ends of the arms being similarly curved forwardly so as to pass through the loops or handles

5 formed on a bag, and means provided at the connection of the arms to the standard for holding the arms at any adjusted position, substantially as described.

9. A bag-holder comprising an upright rod
10 forming a standard, **T**-shaped couplings receiving the rod and arranged at the ends thereof, and substantially duplicate approximately

U-shaped portions consisting of upper and lower arms having their inner ends connected with the standard by the **T**-shaped couplings, 15 substantially as described.

In testimony that I claim the foregoing as my own I have hereto affixed my signature in the presence of two witnesses.

CHARLES W. LANPHER.
